UNITED STATES PATENT OFFICE.

SAMUEL R. STAMBAUGH, OF CHATTANOOGA, TENNESSEE.

ROCKER.

No. 826,380.

Specification of Letters Patent.

Patented July 17, 1906.

Application filed March 3, 1905. Serial No. 248,268.

To all whom it may concern:

Be it known that I, SAMUEL R. STAMBAUGH, a citizen of the United States, residing at Chattanooga, in the county of Hamilton and State of Tennessee, have invented certain new and useful Improvements in Rockers, of which the following is a specification.

My invention relates to an improvement in rockers used in the concentration of ores; and the object is to provide means for catching the very fine gold which hitherto has been wasted.

With these objects in view my invention consists in a rocker having a plurality of transversely-located semicircular riffles adapted to contain quicksilver in connection with stationary riffle-boards, which also contain quicksilver in their grooves, in which the coarse gold is caught in its descent from the washing-trough above and on the way to the rocker beneath.

My invention further consists in certain novel features of construction and combinations of parts, which will be hereinafter described, and pointed out in the claims.

In the accompanying drawings, Figure 1 is a plan view. Fig. 2 is an end elevation. Fig. 3 is an enlarged longitudinal sectional view, and Figs. 4 and 5 are detached views of the two stationary riffle-boards.

The numeral 1 represents the rocker.

2 is the washing-trough; 3, the coarse-refuse spout; 4 4, arms holding the trough and spout; 5, the hopper; 6, a screw for raising and lowering an end of the rocker; 7, the hinge of the rocker; 8, an elevating-hinge for the frame on which the rocker is supported and which is capable of being raised 40 and lowered at the outer end by the screw 6.

9 9 are rubber bumpers.

10 is a rocker-lever secured, preferably, to one end of the rocker 1.

11 is the main frame of the machine.

45 12 12 are the riffles in the rocker.

13 13 are the riffles in the longer riffle-board.

14 14 are the riffles in the shorter riffle-board.

50 15 is the cleaning-up groove.

16 is the cleaning-out plug, located at one end of the groove 15.

18 is a rod upon which arms 4 4 are hinged so as to permit the trough to be swung aside

into the position indicated by dotted lines in 55 Fig. 2, and 19 19 are hangers by which the stationary riffle-boards are suspended from the trough 2.

While my invention is more particularly adapted for use with my invention disclosed 60 in Letters Patent No. 633,397, issued September 19, 1899, for mining in frozen ground, still of course it is capable of use wherever a rocker may be used in the concentration of precious metals.

65 The rocker is preferably about forty inches in diameter and eight feet in length, with fourteen grooves susceptible of receiving quicksilver, as are also the several grooves in the riffle-boards, which latter are preferably 70 made from solid plank.

75 In operation the gravel or pay-dirt is conveyed in any convenient manner to the hopper, then allowed to descend the inclined steel plate 2', removably carried by the arms 4 4, into the steel trough 2, which latter has a perforated bottom suitable in size for the material to be washed. The plate 2' is slotted near one longitudinal edge to receive one side or wall of the hopper 5, the opposite edge of 80 the plate being cut away to fit within the hopper. The plate bridges the space between the hopper and the trough. The material is forced down into the trough by means of a hoe or rake. If the material is 85 frozen, it is first thawed by steam and thoroughly disintegrated, when it is readily washed by one or more streams or jets of hot water. The coarse gravel too coarse to pass through the perforations of the trough 90 is raked off through the raised curved spout 3 and landed outside of the rocker, while all the fine material drops through the perforations in the trough or screen 2 onto the downwardly-inclined riffle-boards 13 and 14, 95 where it drops into hot water and warm quicksilver in the very first groove of the rocker which is close up to the head end of the rocker. Thence it passes through the other grooves of the rocker, all of which contain 100 quicksilver, to insure the saving of the fine and dust gold, as well as the coarse, which is the only part now saved with the processes in use. In other words, by my invention I save what heretofore has been lost. The 105 longitudinally-extending groove 15 communicates with all of the transverse grooves 12 12 of the rocker, and into this one groove 15

the quicksilver in the others may be emptied to facilitate cleaning up. The transverse grooves in the rocker come within six inches of the top of the rocker, terminating in the 5 cleaning-up groove. By removing the rocker from its hinges and turning it on the one side all the grooves 12 12 can be washed into the one groove 15, and the quicksilver can be emptied into a pan through the plug-hole 16, 10 and the heavy amalgamated gold in groove 15 can be readily spooned out. By turning the screw 6 the inclination of the rocker is regulated for the different grades of material to be washed, the head end of the rocker resting on a rigid beam 17, while the beam 17' is hinged at 8, the screw operating to raise or lower it. The trough 2, spout 3, and riffle-boards 13 and 14 always remain stationary while at work, while the rocker 1 underneath 15 is oscillated to facilitate the saving of the very fine gold. When it is desired to clean up the machine, the trough is swung back into the position shown in dotted lines in Fig. 2, and the arms 4 4 may be weighted, if desired, at their extreme ends to counterbalance the weight of the trough and spout and make the elevation of the latter as easy as possible.

From the foregoing it will be seen that a 30 simple means is provided for catching and saving the fine particles of precious metals which would otherwise be lost.

It is evident that slight changes might be resorted to in the form and arrangement of 35 the several parts described without departing from the spirit and scope of my invention, and hence I do not desire to limit myself to the exact construction herein set forth; but,

40 Having fully described my invention, what I claim as new, and desire to secure by Letters Patent, is—

1. A rocker comprising a curved interior surface, a series of riffles extending transversely of the rocker and conforming in shape therewith, the riffles comprising a series of successive parallel inclines, the lowest point of one incline connected with the highest point of the succeeding incline by means 45 of an undercut groove, the interior surface of the rocker provided with a longitudinally-extending groove intersecting each of the undercut grooves, and means for laterally rocking the rocker, and for periodically tilting 50 the same.

2. In a rocker, the combination with a curved interior surface, of a series of transversely-extending riffles with undercut grooves covering the interior surface of the 55 rocker and conforming in shape therewith, the rocker further provided with a longitudinally-extending groove intersecting the riffles, and communicating with an aperture through which the groove is drained, the

groove normally occupying a position relative to the riffles which prevents it from containing the concentrates and means for oscillating the rocker laterally and for periodically tilting the rocker into position to deliver the concentrates to the groove. 65

3. A rocker comprising a body portion, riffles extending transversely thereof, the body portion further provided with transversely-extending grooves, means for oscillating the rocker laterally, the body portion 75 further provided with a longitudinally-extending groove adapted to receive the contents of the transversely-extending grooves, the longitudinally-extending groove normally occupying a position which prevents it 80 from retaining the concentrates, the rocker being adapted to be tilted to discharge the concentrates into the groove.

4. The combination with a suitably-supported rocker, and means for oscillating the 85 same laterally, of a screen-trough stationarily located above the upper open side of the rocker, stationary riffle boards located beneath the trough, each riffle-board adapted to receive material directly from the screen, 90 and one of said boards discharging onto the other of said boards, the riffle-boards located within the rocker.

5. The combination with a semicylindrical rocker, a series of transversely-extending riffles formed in the curved interior of the rocker and conforming to the curved surface of the rocker and means for oscillating the rocker laterally, of a screen for receiving the ore to be treated, the screen normally stationarily 95 supported within the horizontal plane of the upper edges of the rocker, riffle-boards suspended from and beneath the screen and within the rocker, and a curved discharge-spout secured to one end of the screen and 100 passing over one edge of the rocker.

6. The combination with a riffled rocker and means for oscillating the same, of a frame disposed adjacent the rocker, arms pivotally secured to the frame, a hopper carried by the frame, a screen mounted on the arms, at one end thereof, and a plate carried by the arms and bridging the space between the hopper and the screen. 110

7. The combination with a riffled rocker 115 and means for operating the same, of a frame located adjacent the rocker, a hopper carried by the frame, arms pivotally secured to the frame, the rear ends of the arms taking beneath and limited in their movement in one 120 direction by the frame, a hopper carried by the opposite ends of the arms and normally located above the rocker and a plate removably carried by the arms and bridging the space between the hopper and screen. 125

8. The combination with a riffled rocker and means for rocking the same, of suitable framework located adjacent to the rocker,

means carried by the framework for receiving the ore and feeding it to the rocker, a beam hinged at one end to the framework, its other end supporting the rocker, and means for raising and lowering the free end of this hinged beam whereby to regulate the inclinations of the rocker.

In testimony whereof I affix my signature in presence of two witnesses.

SAMUEL R. STAMBAUGH.
